STANLEY J. TURREFF, OF NEW YORK, N. Y., ASSIGNOR TO FEDERAL SIGNAL COMPANY,
OF ALBANY, NEW YORK, A CORPORATION OF NEW YORK.

RAILWAY SIGNALING SYSTEM.

1,317,645.

Specification of Letters Patent. Patented Sept. 30, 1919.

Application filed February 17, 1919. Serial No. 277,418.

To all whom it may concern:

Be it known that I, STANLEY J. TURREFF, a citizen of the United States, and a resident of the city, county, and State of New York, 5 have invented certain new and useful Improvements Relating to Railway Signaling Systems, of which the following is a specification.

My invention relates to improvements in 10 railway signaling systems for railroads. An object of my invention is to compel an observance of the warning given by the signals. In my invention, if the warning of the signal is observed by the engine driver, 15 and he retards the speed of the vehicle, car or train in obedience to it, an audible signal device does not sound; but if the engine driver has not observed the warning given by the signal and acted in obedience thereto, 20 the audible alarm device sounds, thereby warning the engine driver, or other members of the crew, or both, that he or they must act in some way to retard the car or train. The audible alarm device is located 25 at such a point that if and when it has sounded, sufficient distance is left in which to retard the car or train or bring it under control to prevent an accident, such as a collision, derailment, etc.

30 I will describe a signaling system and the improvements embodying my invention applied thereto, and then point out the novel features thereof in claims.

In the accompanying drawings, all of 35 which are diagrammatic, Figure 1 is a view of a portion of a trackway to which is applied a signaling system for the control of cars or trains along the trackway, and embodying my invention. The signals, relays, apparatus, etc., are shown in the positions intended for them when no car or train is present on the trackway, and the circuits controlling them are shown in the condition which compels the position of such signals, 40 relays, etc. Fig. 2 is a similar view of the trackway and signaling system shown in Fig. 1, except that certain signals, relays, apparatus, etc., are in a different position and the circuits controlling them in a different condition due to the presence of a car or train on a portion of the trackway. Fig. 45 3 is a similar view of the trackway and signaling system shown in Fig. 1, except that certain signals, relays, apparatus, etc., are in a different position and the circuits

controlling them in a different condition due to the presence of two cars or trains on two different portions of the trackway. Fig. 4 is a view similar to Fig. 3, except that certain signals, relays, apparatus, etc., are in a 60 different position and the circuits controlling them in a different condition due to the presence of two cars or trains on two different portions of the trackway, and due also to the fact that the driver of the car or 65 train to the left did not obey the warning given by the signal at the left of the figure.

Similar letters of reference designate corresponding parts in all the figures of the 70 drawings.

Referring to the drawings, R designates a trackway of a steam or electric railway, and divided into signaling sections, generally termed "block sections." Two complete signaling sections are shown designated A 75 and B, and portions of two other sections. Any of the well-known methods for dividing the trackway into signaling sections may be employed. As shown, both rails of the trackway are provided with insulated 80 joints 1^a.

Each signaling section is provided with a "track circuit," which track circuit, as usual, comprises a source of current and a relay device both connected with the opposite track rails of the signaling section so as to form a continuous path, closed at all points, for the flow of signaling current from a suitable source. a¹ is the source of 85 signaling current for the track circuit in 90 signaling section A, and b¹ the source of signaling current for the signaling section B. a² is the relay device included in the track circuit for signaling section A, and b² the relay device included in the track circuit 95 for signaling section B. The relay devices a², b² may be any of the well-known types and according to whether the sources of current a¹, b¹ supply direct or alternating current. Each relay device is provided with 100 an armature which carries one or more contact fingers which coact with front and back contacts to open and close circuits. In the drawings each contact finger is diagrammatically represented with an armature. 105

In carrying out my invention, I provide each signaling section with an additional track circuit, the relay of which preferably also functions in the signaling system applied to the trackway, and which track cir- 110

cuit directly acts in the control of an audible alarm device involved in my invention. The additional track circuit for each signaling section A, comprises a source of current 5 a^5 , the opposite rails of the signaling section and a relay device a^6 . The source of current a^5 may be the same or different from the source a^1 , b^1 , and the relay device a^6 the same as or different from the relay device 10 a^2 , b^2 .

At the entrance end of each signaling section I locate a suitable signal device, A^1 being the signal device for section A, and B^1 the signal device for section B. The signal devices are preferably of the automatic type comprising a mechanism and a semaphore blade and an operating mechanism for moving the blade to two positions of indication, here shown as in the upper quadrant, and designated "clear" and "caution," and for permitting the blade to move by gravity to a third position indicating "danger."

The relay device in each signaling section 25 primarily controls the operation of the mechanism of the signal device provided for that signaling section, in its movement of the blade to its "clear," "caution," or to permit the blade to move by gravity to its 30 "danger" positions. When the relay devices, for example, b^2 , a^6 (see Fig. 2), or either of them are deenergized, due to the presence of a car or train in their signaling section, a circuit is opened which includes a relay device Y and a circuit is also opened which includes a relay device X, and the opening of these circuits permits the blade to assume its "danger" position of indication by gravity. When the car or train moves into the 40 next signaling section the same operation above described takes place with respect to the signal device for that signaling section. When the car or train has left a signaling section (assume in Fig. 2 that the car or train has left section A and entered section 45 B), the relay devices of the section so vacated again becomes energized, and the relay device Y of the same section becomes energized to move the blade of the signal device 50 to its "caution" position of indication. The relay device X of the same signaling section is not energized because its control also includes a front contact of the relay device Y of the signaling section in advance (in 55 this case section B) and which is now occupied by the car or train. This system of signal indications is very well known in the art as are the circuits, relay devices, etc., for causing the mechanism of the signal devices to produce the signal indications, and hence will not be described in detail. The necessary circuits, relay devices, etc., for practising such a system of signal indications are shown in the drawings.

60 H designates a suitable automatic audible

alarm, which comprises a bell or other sound producing device h and an electrically operated or controlled mechanism h^1 . The preferable arrangement in the alarm device H is, that, so long as current is present in the 70 mechanism h^1 , the sound device h is silent, but when current is not present in the mechanism h^1 the device h sounds immediately and continuously. One such alarm device H is provided for each signaling section and 75 is located at a point therein, that if and when sounded, sufficient distance is left to retard the car or vehicle, which caused the alarm to operate, before reaching the danger point. For example and referring to Fig. 80 2, with a train in signaling section B, the blade of the signaling device B^1 is in its "danger" position, in which position it warns the driver of an approaching train that the signaling section is occupied by a 85 car or train, and the blade of the signal device A^1 is in its "caution" position, in which position it warns the driver of an approaching car or train to reduce its speed prepared to stop, as the next block in advance is occupied by a car or train. If then the driver of a car or train about to enter signaling section A does not observe the position of the blade and act in obedience to its warning, the audible alarm is set into 90 operation at a point which, if the driver or other member of the train crew then acts, will enable the train to be stopped before reaching the signaling section B. This is the situation illustrated in Fig. 4. If, however, the driver of such a car or train did observe the position of the blade of the signal device A, and obeyed its warning by reducing the speed of his car or train sufficiently to consume an amount of time in 100 traveling through the first part of the signaling section equal to or greater than that for which the "time element relay" G is adjusted, the alarm device H will not sound. This is the situation illustrated in Fig. 3. 110

Referring now to Fig. 1, with no car or train present in a signaling section, a circuit, which includes the mechanism h^1 , is maintained through the alarm device H, which circuit may be traced as follows:— 115 source of current I, wires 1, 2, 20, armature of relay device a^6 , contact 21, wires 22, 23, mechanism h^1 , and wires 6, 7 and 8 to source I. When a car or train enters a signaling section (for example from A to B in Fig. 2) 120 with the blade of the signal mechanism B in its "clear" position of indication, obviously there is no reason why the alarm H should be sounded. Hence, a circuit is established which may be traced as follows:—source of current I, wires 1, 9, armature of first track relay, back contact point 10, wires 11, 12, contact finger o of a circuit controller included in the signal mechanism, contact o^1 (which at the time assumed is 125 130

engaged by the finger o) wire 13, relay device F, and wires 14, 7 and 8 to source I. Immediately that the relay F is energized, it closes a circuit on itself (a stick circuit) as follows: source of current I, wires 1, 9, 15, armature of relay device Y (which is de-energized when the car or train enters the signal section), back contact 16, wire 17, armature of relay F, contact 18, wires 19, 10 13, relay F and wires 14, 7 and 8 to source I. Consequently, when the finger o moves away from contact the relay F is still energized and a circuit is established on the alarm H as follows:—source of current I, 15 wires 1, 2, 3, armature of relay F, contact point 4, wire 5, mechanism h^1 , and wires 6, 7 and 8 to source I. Hence, when the car or train shunts relay device a^6 to open the circuit on the alarm device maintained by 20 it, the alarm is not sounded because of the circuit being closed by the relay F. When the car or train leaves the signaling section (for example A in Fig. 2) the circuit just traced (stick circuit) is broken at contact 25 16 (due to relay device Y being energized) and the condition of apparatus and circuits for signaling, section B is that shown for signaling section A, Fig. 2, and the condition of apparatus for signaling section 30 A that shown in Fig. 1.

Referring now to Fig. 2, if a car or train should enter signaling section A and the driver thereof observes the position of the blade of the signal device A and obeys its 35 warning by reducing the speed of the car or train, as soon as relay device a^2 is de-energized a circuit is established through a “time element relay” G to initiate its operation, and which circuit may be traced as 40 follows:—source of current I, wires 1, 9, armature of relay a^2 , back contact point 10, wires 11, 30, contact finger o^2 of the circuit controller included in the signal mechanism, contact o^3 , wires 31, 32, contact 33, armature 45 of relay F, wire 34, “time element relay” G, and wires 35, 36, 37, 14, 7 and 8 to source I. The “time element relay” G is of any well-known construction, and comprises as usual an electrically operated or controlled 50 means which, when energized, immediately sets into operation a suitable mechanism involving an adjustable time element. This mechanism therefore after a pre-determined lapse of time picks up its armature to close 55 a circuit, which in this instance includes the mechanism h^1 of the alarm device. This circuit, which is assumed to have been established in Fig. 3, because of the operation of the “time element relay” G, is as follows:—source of current I, wires 1, 9, 100, 60 member g of the “time element relay” G, contact 40, wires 41, 5, mechanism h^1 and wires 6, 7 and 8 to source I. Therefore if the car or train which entered signaling 65 section A, reduced its speed sufficiently to

enable the “time element relay” G to complete its operation to close the circuit just described, the alarm device H will not be sounded when the relay a^6 is de-energized because another circuit (a stick circuit) will be established on the “time element relay” G which may be traced as follows:—source of current I, wires 1, 2, 20, 44, back contact 45 of relay a^6 , armature a^4 , wire 46, armature g of “time element relay” G, front contact 48, wire 49, “time element relay” G and wires 35, 36, 37, 7 and 8 to source I. The circuit which includes the contact point 40 and alarm H will be thus maintained to prevent the alarm sounding. This condition of circuits and apparatus is illustrated in Fig. 3. If, however, the driver of the car or train entering section A (Fig. 2) did not observe its position and therefore did not obey its warning, the “time element relay” G will not have had time to pick up its armature and hence when relay a^6 is shunted, all circuits provided for the alarm H will be open and the alarm will then sound. This condition of circuits and apparatus is illustrated in Fig. 4. All members of the crew or other persons will be warned that a dangerous condition exists in that the driver of the car or train has disregarded the warning of a “caution” signal and that some action must be taken to prevent an accident.

It will be understood that by the term “caution” I mean to include any condition of trackway which requires a reduction of speed of the vehicle to insure safe conditions under which the vehicle may be moved.

Having thus described my invention, what I claim as new and desire to secure by Letters Patent is:—

1. The combination in a signaling system comprising a signal device automatically controlled by the condition of a portion of the track in advance of said signal device to give a “caution” warning, an alarm device located in advance of the signal device, a circuit for said alarm device which when closed will prevent the alarm device sounding, an electrically operated time device for controlling said circuit, and a circuit including said time device which is initially closed by a car or train after it passes said signal device in its “caution” position.

2. The combination in a signaling system comprising a signal device automatically controlled by the condition of a portion of the track in advance to give a “caution” warning, an alarm device located in advance of the signal device a normally closed circuit for said alarm device, vehicle controlled means for opening said circuit, a second circuit for said alarm device and normally open, a time element device for closing said circuit after the lapse of a predetermined period of time, and vehicle con-

- trolled means for initiating the operation of said time element device.
3. The combination in a signaling system comprising a signal device automatically controlled by the condition of a portion of the track in advance to give a "caution" warning, an alarm device located in advance of the signal device, train controlled means to normally keep it from sounding,
- 10 5 a time element device which after a pre-determined lapse of time also acts to prevent the alarm sounding, and train controlled means for initiating the operation of the time element device.
- 15 10 4. The combination in a signaling system comprising a signal device automatically controlled by the condition of a portion of the track in advance to give a "caution" warning, an alarm device, a circuit for said alarm device which is normally held closed by a track relay, a second circuit for said alarm device, a time element device for

20 closing said circuit, and vehicle controlled means for initiating the operation of said time element device.

25 5. The combination in a signaling system comprising a signal device which gives warning indications of the condition of the track in advance, an alarm device located in advance of the signal device, means for normally keeping the alarm device from sounding, and means for also keeping the alarm device from sounding after a pre-determined lapse of time, which means are initially operated by the action of a car or 30 train.

35 In witness whereof, I have signed my name to this specification, in the presence of two subscribed witnesses.

STANLEY J. TURREFF.
